UNITED STATES PATENT OFFICE.

JOSEPH ETIENNE PRÉGARDIEN, OF KALK, GERMANY.

APPARATUS FOR PURIFYING GAS.

SPECIFICATION forming part of Letters Patent No. 769,713, dated September 13, 1904.

Application filed September 23, 1901. Serial No. 76,305. (No model.)

To all whom it may concern:

Be it known that I, JOSEPH ETIENNE PRÉGARDIEN, a subject of the Emperor of Germany, residing at Kalk, Rhineland, Germany, 5 have invented certain new and useful Improvements in Gas-Purifying Apparatus, set forth in the following specification.

In the apparatuses for purifying gas already known, in which single condensing-chambers 10 are connected by means of pipes to form a continuous series, there is the drawback that for cleaning out single chambers the whole series must be put out of use and the manufacture thereby interrupted.

15 The present invention is for the purpose of enabling single condensing-chambers to be cleaned without interrupting the process. This is effected by inserting in each pipe, connecting two condensing-chambers with each 20 other, a double and single plug, which allows a communication being made between one chamber and the next or shutting off this latter and making connection with a pipe discharging into the main connecting-pipe above 25 the plug.

In the accompanying drawings, Figures 1 to 3 illustrate diagrammatically one constructional form of the invention. Fig. 4 shows another form of construction.

30 The special construction of my invention may be more clearly followed by reference to the characters on the drawings.

The suitably-cooled condensing-chambers 1 2 3 4 5 are connected in a series by means 35 of outlet-pipes b' , b^2 , b^3 , b^4 , and b^5 , which are secured in the upper end of each chamber and are connected with a main gas-carrying pipe d . Extending into each chamber are 40 pipes a' , a^2 , a^3 , a^4 , and a^5 , which are connected to the main supply-pipe d for conducting the gases into the condensers, wherein are separated the impurities in the gases.

Upon each of the inlet and outlet pipes, just above the top of the condensing-chambers, are dish-shaped extensions c' to c^{10} , into which are fitted pipe-sections g g' , which are greater in cross-section than the ends of the

inlet and outlet pipes and adapted to permit of the movement therein of valves h h' . These pipe-sections g g' are hermetically sealed in 50 said extensions or sealing-grooves c' to c^{10} , and main supply-pipe d connects through them with inlet-pipes a' to a^5 upon the plugs h h' being lifted out of their seats. At the upper end of the pipe-sections are inserted pipes f , 55 whose ends are adapted to seat valves h . These pipes f are connected by pipes d' to d^5 to the pipe-sections g' of the outlet-pipes b' to b^5 .

The valves h h' are so arranged by means of chains i i' , which are wound around drums e' to e^5 , as to be lifted upon the rotation of said drums off their seats upon the upper ends of the inlet and outlet pipes, which extend into the pipe-sections g g' and to close the pipes f , while at the same time opening the 65 inlet and outlet pipes leading to the condensers 1 to 5. By this means gas from the main supply-pipe is admitted to the condensers, or by seating the valves upon the inlet and outlet pipes of one or more condensers communication to said condensers may be closed and the gas flow by pipes d' to d^5 to the other condensing-chambers. In this manner any one 70 of the series of condensing-chambers may be cut out without retarding the process of purification.

In Fig. 4 is shown a slightly-modified structure wherein the pipes a' to a^5 are upon the outside of the condensing-chambers, the gases having first to pass through cross-pipe x when 80 the plug-valves h are in the position shown before being carried through the condensing-chamber and through the outlet-pipes to the next of the series. y is a receptacle containing a liquid to form a seal with l and a' . 85

Having now particularly described and ascertained the nature of my said invention and in what manner the same is to be performed, I declare that what I claim is—

In a gas-purifying apparatus, the combination of a series of condensing-chambers, inlet-pipes communicating therewith, a series of outlet-pipes connected to said chambers, inclined pipes communicating with said inlet 90

and outlet pipes, a series of by-pass pipes connecting said outlet and inlet pipes, a plug-valve, arranged in said outlet and inlet pipes of each condensing-chamber, and means to 5 operate the valves simultaneously, to cut out or in one or more of said chambers of the series, substantially as described.

In witness whereof I have hereunto set my hand in presence of two witnesses.

JOSEPH ETIENNE PRÉGARDIEN.
